UNITED STATES PATENT OFFICE.

PERRY S. MARTIN, OF BROADWAY, VIRGINIA.

TEMPERATURE-REGULATING DEVICE FOR HEATERS.

1,192,335.

Specification of Letters Patent. Patented July 25, 1916.

Application filed October 27, 1914. Serial No. 868,796.

To all whom it may concern:

Be it known that I, PERRY S. MARTIN, of Broadway, in the county of Rockingham and State of Virginia, have invented certain new and useful Improvements in Temperature-Regulating Devices for Heaters, whereof the following is a specification, reference being had to the accompanying drawings.

My invention relates to a heater adapted for use with a brooder for raising young chickens, and is particularly applicable to such use, and I have shown and will describe my invention as thus applied.

In my device the regulation is applied alternatively to a check draft for satisfying the flue, and to a main draft for admitting air to the combustion chamber. To render the regulation more automatic and certain, these two apertures are arranged in close proximity and in opposition to each other, so that a single valve thermostatically controlled, may reciprocate between the two, covering one or the other aperture or occupying any intermediate position between the two.

In the accompanying drawings, Figure I, is a vertical section of a brooder heater having applied to it my invention. Fig. II, is a horizontal section along the line II, II, of Fig. I. Fig. III, is a partial section on an enlarged scale showing the automatic regulator in detail.

The heater 1, is provided with a grate 2, suitable for burning solid fuel and below which is the ash pan 3, and the ash door 4. The upper part of the heater constitutes the combustion chamber proper, and is provided with a top 5, within which is set a magazine 6, with a feed opening 7.

Surrounding the upper part of the combustion chamber is an annular drum or heat radiator 8. The combustion chamber communicates with the drum 8, by an opening 10. (See Fig. II). A flue 11, draws the heated products of combustion from the drum 8. A depending-sleeve 12, forms a lower prolongation of the flue 11, and compels the flue to draw from near the bottom of the drum 8, through the lower aperture 13, of the sleeve 12. Just below this flue aperture 13, is located the larger check draft aperture 14, by which the drum communicates directly with the outer atmosphere, permitting the draft of the flue to be satis-

fied without the passage of air through the combustion chamber.

A large deflecting hood 15, in the shape of a conical annulus is set around the top of the heater, for retaining the warmth of the heater within the space immediately surrounding it as customary in brooder heaters of this type.

At the side of the heater which corresponds to the position of the aperture 14, there is provided a curved pipe 20, which enters the heater and communicates with the combustion chamber by way of the grate 2. By this pipe, is supplied the main draft which passing through the pipe feeds the combustion. The upper aperture 21, of this main draft pipe 20, is in immediate proximity to and in opposition to the check draft aperture 14, heretofore described. Between these two apertures is the double valve 22, comprising a central stem 23, and two disk shaped plates 24. The two disks form in substance one valve capable of governing alternatively the two opposed apertures 21, and 14, according to the position in which the valve is placed.

The use of the double disks is largely for the purpose of making a lighter valve and securing a more accurate setting of the same. This valve is carried by an arm 25, pivoted at 26, and counterbalanced by a weight 27. The pivot 26, is sustained by a fixed member 28, attached rigidly to the side of the heater, as for example, by means of the arm 29, to the pipe 20. An upright rod 30, threaded at the top, passes through the arm 25, near the pivot, its relation thereto being capable of adjustment by the milled nut 31. The lower end of this rod 30, is connected by a link 32, to a fulcrum 33, set in fixed relation to the member 28, upon which the parts just described are all supported. A thermostat 35, is interposed between the fixed arm 36, in fixed relation to the member 28, and the link 32. By the expansion of this thermostat the rod 30, is depressed, in turn depressing the valve 22, until it seats itself upon the upper extremity of the main draft aperture 21. In this position the main draft is closed and the check draft wide open. As the air under the hood 15, cools, the thermostat contracts allowing the valve to rise until it comes into contact with the check aperture 14. In the latter position, the main draft aperture 21, is

wide open and the check draft aperture 14, closed. In the intervening positions, the draft is fed in varying proportions either to the feed opening or the check opening according to the position of the thermostat.

I am aware that in previous constructions, automatic regulating devices have been arranged to simultaneously control a main valve and a check valve, but by reason of the distance between these valves and their irregular positions upon the heater, various moving parts have been required to connect them to the regulating device, introducing not only additional weight in the moving parts of the regulator, but affording possibilities for mal-adjustment which have led to trouble and failure of the regulator. By arranging the main draft opening and check draft opening near together and in immediate opposition, I am enabled to employ substantially one valve for the purpose of regulating both apertures, and correspondingly to simplify the entire thermostat connection.

It is a further advantage of my arrangement that by the juxtaposition of the two openings 14, and 21, the draft which feeds the flue, no matter what may be the position of the thermostat, is always drawn from substantially the same part of the space beneath the hood 15. In a brooder it is of importance that the draft shall be thus constantly fed from beneath the hood in order that a circulation of fresh air may be insured in the space beneath the hood, which is occupied by the chicks. It is further important that this draft shall be always drawn from the same place so that it shall be uniform in its movement, securing an even temperature in any given part of the space beneath the hood. This is attained by the construction which I have described.

Having thus described my invention, I claim:

1. In a brooder heater, the combination of a combustion chamber, a deflector hood surrounding the same; said combustion chamber being provided with a grate, and having

a main draft aperture and a check draft aperture of substantially the same size and in proximity to each other both beneath the deflector hood and a valve capable of alternatively controlling either aperture, and permitting the draft of either to be satisfied with air from beneath the deflector hood whereby a substantially uniform circulation of air is always maintained beneath said deflector hood.

2. In a brooder heater, the combination of a combustion chamber; a deflector hood surrounding the same, said combustion chamber being provided with a grate and a main draft aperture beneath said deflector hood; an annular drum surrounding the upper part of the combustion chamber and a flue leading from the combustion chamber by way of the drum, said drum being also beneath said hood and provided with a check draft aperture in proximity to the main draft aperture, and a valve capable of alternatively controlling either aperture and satisfying the draft with air from beneath the deflector hood.

3. In a heater provided with a combustion chamber, a grate and a main draft aperture, an annular drum surrounding the upper part of the combustion chamber and communicating therewith; a flue leading from the combustion chamber by way of the drum; a depending sleeve forming a prolongation of the flue within the drum, said drum having a check draft aperture adjacent the lower end of said sleeve and also adjacent the main draft aperture, a valve capable of alternatively controlling either aperture and thermostatic means for controlling the same.

In testimony whereof, I have hereunto signed my name at Harrisonburg, Virginia, this 23rd day of October, 1914.

PERRY S. MARTIN.
